United States Patent

Des. 236,120
Patented July 29, 1975

236,120

COMBINED TOILET SEAT AND COVER

Robert O'Neil, Wheaton, Ill., assignor to Beneke Corporation, Columbus, Miss.

Filed Oct. 26, 1973, Ser. No. 409,880

Term of patent 14 years

Int. Cl. D23—02

U.S. Cl. D23—71

FIG. 3

FIG. 4

FIG. 5

FIG. 6

FIG. 1 is a perspective view of a combined toilet seat and cover embodying my new design, the cover being shown in an open position;

FIG. 2 is another perspective view thereof, showing the cover closed;

FIG. 3 is a top plan view of FIG. 1;

FIG. 4 is a front elevational view of FIG. 1;

FIG. 5 is a side elevational view of FIG. 1; and

FIG. 6 is a bottom plan view of FIG. 1.

I claim:

The ornamental design of a combined toilet seat and cover, substantially as shown.
